DESIGN FOR A COMBINED DOOR KNOCKER
AND WICKET

Allen Bloom, New York, N. Y.

Application October 15, 1947, Serial No. 141,903

Term of patent 7 years

(Cl. D10—7)

To all whom it may concern:

Be it known that I, Allen Bloom, a citizen of the United States and a resident of the city of New York, in the county of Queens and the State of New York, have invented a new, original, and ornamental Design for a Combined Door Knocker and Wicket, of which the following is the specification, reference being had to the accompanying drawing, forming part thereof.

Figure 1 in the drawing is a front view of a combined door knocker and wicket showing my new design;

Figure 2 is a side view of the combined door knocker and wicket;

Figure 3 is a vertical section of the combined door knocker and wicket taken on the line 3—3 of Figure 1;

Figure 4 is a bottom view of the combined door knocker and wicket; and

Figure 5 is a top view of the combined door knocker and wicket.

I claim:

The ornamental design for a combined door knocker and wicket, substantially as shown and described.

ALLEN BLOOM.
